[57] CLAIM

The ornamental design for a free access floor panel, as shown and described.

DESCRIPTION

FIG. 1 is a top plan view of a free access floor panel showing our new design;

FIG. 2 is a bottom plan view thereof;

FIG. 3 is a front elevational view thereof, the rear elevational view being a mirror image thereof;

FIG. 4 is a right side elevational view thereof, the left side elevational view being a mirror image thereof;

FIG. 5 is an enlarged cross-sectional view taken along line A—A of FIG. 2;

FIG. 6 is an enlarged cross-sectional view taken along line B—B of FIG. 2;

FIG. 7 is an enlarged cross-sectional view taken along line C—C of FIG. 2;

FIG. 8 is an enlarged cross-sectional view taken along line D—D of FIG. 2; and,

FIG. 9 is a side elevational view thereof, the broken lines showing adjacent floor panels and supports are for illustrative purposes only and form no part of the claimed design.

FIG. 1

FIG. 2
